UNITED STATES PATENT OFFICE.

OLE EVINRUDE, OF MILWAUKEE, WISCONSIN, ASSIGNOR TO EVINRUDE MOTOR CO.,
OF MILWAUKEE, WISCONSIN.

MARINE PROPULSION MECHANISM.

1,087,162.

Specification of Letters Patent. Patented Feb. 17, 1914.

Application filed October 12, 1912. Serial No. 725,358.

To all whom it may concern:

Be it known that I, OLE EVINRUDE, a citizen of the United States, and resident of Milwaukee, in the county of Milwaukee and 5 State of Wisconsin, have invented certain new and useful Improvements in Marine Propulsion Mechanism; and I do hereby declare that the following is a full, clear, and exact description thereof.

10 My invention consists in what is herein particularly set forth with reference to the accompanying drawings and pointed out in the claims of this specification, its main object being to provide for ready compensation 15 for wear caused by end-thrust of propeller-shafts and gear-thrust thereon, especially in the marine propulsion mechanism disclosed in United States Letters Patent No. 1,001,260, granted August 22, 1911.

20 Figure 1 of the drawings represents a partly sectional side elevation of marine propulsion mechanism similar to that disclosed in the Letters Patent aforesaid and embodying the improvements herein specified; Fig. 2, a central longitudinal sectional view of an adjustable bushing constituting a novel essential part of said mechanism, and Fig. 3, a cross-section of the bushing indicated by line 3—3 in Fig. 2.

25 Referring by numerals and letters to the drawings, 25 indicates a lower sliding section of a vertical engine-shaft, 15 a stationary tube concentric with the shaft, 16 another tube adjustable on the one aforesaid, 30 17 a gear-case having a shaft-bearing extension 17' thereof upon which the lower end of the tube 16 is detachably secured, 26 a propeller, 26' the propeller-shaft in miter-gear connection with said sliding section of 35 the engine-shaft, 27 a pump-cylinder, 28 a hose leading from the pump-cylinder and 29 on the pump-piston operated by a cam 30 on the hub of the gear-wheel of said propeller-shaft.

40 The general construction and arrangement of parts to which reference is had in the foregoing is similar to what is disclosed in the Letters Patent above noted, and they are correspondingly indicated. Like in said 45 Letters Patent, the tube 16 is provided with a rigid outer collar 18 adjustable longitudinally of a supporting bracket arm 13' but this detail constitutes no part of what is herein claimed, and is only incidentally 50 shown.

The essential novel feature of what is herein claimed is an adjustable bushing B in the forward horizontal bearing-box end of the gear-case 17, the bushing being arranged to have its rim at one end in contact with a shoulder fast on a driven-shaft to thus resist gear-thrust on the shaft, and it is preferable to provide said gear-case with a depending guard-fin F in advance of the propeller.

The bushing B is externally screw-threaded and closed at its forward end to thereby exclude water from the gear-case, this end being preferably cone-pointed and provided with a kerf b with which to engage a turning tool such as a screw-driver, but without departure from my invention as herein claimed, the closed outer end of said bushing may be otherwise adapted for engagement with a turning-tool. The bore of the forward bearing-box end of the gear-case is screw-threaded to match the thread of the bushing, and said bushing is set to have its inner end in opposition to the hub of the propeller-shaft gear-wheel that constitutes a wear-shoulder on said shaft, it being held in adjusted position by a set-screw S with which the gear-case is provided. The propeller-shaft has end clearance in the bushing, and said bushing is provided with a series of apertures c at predetermined regular intervals spirally of its circumference, these apertures being for the engagement of the set-screw S in serial order beginning with the one aftermost. However other means may be employed for securing the bushing in rotary adjusted position without departure from my invention as herein claimed.

Coincidental to end-thrust of the propeller-shaft there is wear of the rim of the after end of the bushing and incidental to gear-thrust on said shaft there is also wear upon the underlying portion of said bushing. To take up said wear, the set-screw S is loosened and the bushing is adjusted aft in the gear-case from time to time. A quarter turn of the bushing in the proper direction will suffice to compensate for the aforesaid wear, and hence the apertures in said bushing for engagement serially of the set-screw S may be at quarter intervals of a circle as herein shown, or they may be at greater or less intervals apart.

The bushing takes the wear that would

otherwise come upon the gear-case, making it necessary to renew the same from time to time, at no greater expense than is involved in the substitution of a new for a worn bushing. The bushing also renders hardening of the forward bearing-box end of the gear-case unnecessary, and said bushing is of wear-resisting material in order to prolong its utility.

10 I claim:

1. In a marine propulsion mechanism, a gear-case, a bushing longitudinally adjustable in the forward bearing-box end of the gear-case and having a closed forward end adapted for engagement with an adjusting-tool, a propeller-shaft having an end thereof in the bushing, and a wear-shoulder on the shaft opposing the rim of the after end of said bushing upon which it has thrust.

20 2. In a marine propulsion mechanism, a gear-case, a bushing longitudinally and rotatably adjustable in the forward bearing-box end of the gear-case and having a closed forward end adapted for engagement with an adjusting-tool, a propeller-shaft having an end thereof in the bushing, and a wear-shoulder on the shaft opposing the rim of the after end of said bushing upon which it has thrust.

25 30 3. In a marine propulsion mechanism, a gear-case, a bushing serving to compensate for the wear of said end thereof and its rotary adjustment serving to compensate for wear therein under said shaft upon which gear thrust is exerted.

35 3. In a marine propulsion mechanism, a gear-case, a propeller-shaft, a bushing longi-

tudinally and rotatably adjustable in the forward bearing-box end of the gear-case and having a closed forward end adapted for engagement with a turning-tool, the after rim-end of the bushing being in contact with a shaft-shoulder to resist gear-thrust on said shaft, and means for securing the bushing in its adjusted position.

4. In a marine propulsion mechanism, a gear-case, a propeller-shaft, a bushing in screw-thread engagement with the forward bearing-box end of the gear-case for aft adjustment to compensate for wear occasioned by end-thrust of said shaft and gear-thrust thereon, the bushing being provided with apertures at intervals spirally of its circumference, and a set-screw with said gear-case for engagement of the bushing apertures in serial order.

5. In a marine propulsion mechanism, a gear-case, a propeller-shaft, a bushing in screw-thread engagement with the forward bearing-box end of the gear-case and having a closed cone-pointed end provided with a kerf in which to engage a turning-tool, and means for securing the bushing in adjusted position.

In testimony that I claim the foregoing I have hereunto set my hand at Milwaukee in the county of Milwaukee and State of Wisconsin in the presence of two witnesses.

OLE EVINRUDE.
